UNITED STATES PATENT OFFICE

2,449,851

CONCRETE PLACEMENT MACHINE

Corwill Jackson, Ludington, Mich., assignor to
 Jackson Vibrators, Inc., Ludington, Mich., a
 corporation of Michigan

Application February 1, 1946, Serial No. 644,921

15 Claims. (Cl. 94—45)

1

This invention relates to improvements in concrete placement machines.

The main objects of this invention are:

First, to provide a concrete placement machine or apparatus which is highly efficient and at the same time well adapted for manual manipulation.

Second, to provide a concrete placement machine or apparatus which may be readily adjusted for use in the laying of concrete slabs or strips of different widths.

Third, to provide a concrete placement machine or apparatus which is adapted for the laying of concrete slabs or strips close to a wall or the like and for use in relatively confined spaces.

Fourth, to provide a concrete placement machine having these advantages which is quite easily operated and which may be manipulated to produce a finished surface and to make a second pass over a surface in the event insufficient material was supplied in the first instance to produce the desired grade or in the event further screeding is desired for finishing purposes or for any other purpose.

Fifth, to provide a machine having these advantages which is comparatively simple in structure and light in weight and at the same time highly efficient.

Objects relating to details and economies of the invention will appear from the description to follow. The invention is defined and pointed out in the claims.

A preferred embodiment of the invention is illustrated in the accompanying drawings, in which:

Fig. 1 is a fragmentary plan view of a machine or apparatus embodying my invention illustrated in operative relation to forms and in relation to a wall to illustrate certain adaptations thereof, the left hand guard or retaining member being omitted, the handle being partially shown in its collapsed position by dotted lines.

Fig. 2 is an enlarged fragmentary view in section on line 2—2 of Fig. 1.

Fig. 3 is an enlarged fragmentary view in section on line 3—3 of Fig. 1.

Fig. 4 is an end elevational view somewhat enlarged looking from the right of Fig. 1.

Fig. 5 is an enlarged fragmentary view on a line corresponding to line 5—5 of Figs. 1 and 4 showing details of the adjustable handle, the latch member for holding the handle in its extended position being shown in disengaged position by dotted lines.

Fig. 6 is an enlarged fragmentary view on a line corresponding to line 6—6 of Fig. 4.

2

Fig. 7 is a fragmentary view showing certain details of the connecting means for the screed members.

The embodiment of my invention illustrated 5 comprises a front vibratory member 1 and a trailing screed 2. These members are desirably plank-like—that is, they may be formed of plank-like pieces of timber disposed vertically edgewise.

The vibratory members are both of such height 10 as to rearwardly support a mass of concrete, the member 1, however, being desirably substantially wider than the member 2 as the member 1 is designed to support the concrete or to permit the concrete to pile up against the same as it is advanced against the concrete.

The vibratory member 1 has an electric motor 3 mounted thereon, the rotor 4 of the motor having an unbalancing weight 5 mounted thereon as is shown by dotted lines in Fig. 3. This results in 20 vibrating the vibratory member 1 at high frequency. The electrical connections to the motor are indicated at 6 but it will be understood that the unbalanced rotor might be driven by a flexible shaft.

The vibratory member and screed are connected 25 to be manipulated as a unit, the connections being of such character as to absorb the vibrations so that the screed member has relatively little vibratory movement or the vibrations are substantially 30 eliminated therefrom. These connections are designated generally by the numerals 7, 7 and 8, 8.

The connections 7 consist of angled bracket members 9 secured to the screed member 2.

35 The angled bracket member 10 is secured to the plate 11 which is in turn connected by the resilient or cushioning members 12 to the rear side of the vibratory member 1 by means of the angled plates 13. Similarly angled plates 14 secured to the front 40 side of the member 1 are connected by the resilient members 15 to the plate 16, bolts 17 extending through the brackets 10 and the bracket 18 on the front side of the plate 16. The bolts are arranged through holes 19 in the vibratory member.

45 To provide for aligning or paralleling the members 1 and 2, tie plates 20 and 21 are bolted to the angle brackets 9 and 10, the bolt openings 22 being of a diameter larger than the securing bolts 23 so that the members may be adjusted relative to 50 each other to bring them into parallel form. This is illustrated in Fig. 7 where the members 1 and 2 are slightly inclined but are in parallel relation. In the other figures they are vertical.

The coupling members 8 comprise the non-extensible flexible tubes 24 formed of pieces of

reinforced hose, the ends of these being engaged on studs 25 on the opposed sides of the members 1 and 2, the members 24 being clamped thereon by the clamps 26 which are similar to hose clamps. This provides an effective coupling or connection for the members 1 and 2, permitting vibration of the vibratory member and minimizing or substantially eliminating the vibration of the screed. The members 1 and 2 are thus connected as a unit and serve to mutually coat in supporting each other for manipulation as a unit upon the forms or other supports 27.

In the embodiment illustrated, the members 1 and 2 are provided with angle iron shoes 28 and 29 respectively.

The handle designated generally by the numeral 30 comprises the outer telescoping tubular section 31 having diverging arms 32 extending rearwardly from its front end, the arms having downturned ends 33 which engage the sockets 34 on the front side of the screed member 2. The section 35 of the handle is provided with a handle bar 36 and is telescopically associated within the section 31 to be collapsed with the rear end of the section 35 projecting rearwardly of the screed member as shown by dotted lines in Fig. 1.

The objects of collapsing the handle are two-fold—one being to permit manipulation of the machine closely in a corner or other confined space, and the other to collapse the handle so that concrete may be dumped in front of the machine without dumping upon the handle or the dumping being obstructed by the handle.

The section 35 is provided with a hole 37 adapted to receive the bolt 38 when the handle is in completely extended position, the handle being provided with a second hole 39 for receiving the bolt when the handle is in collapsed position.

When in its extended position, the handle is connected to the vibratory member by means of the latch 40 which has a stud 41 adapted to engage the hook 42 on the vibratory member 1, see Fig. 5. The latch 40 has a flexible section 43 by which the stud 41 is carried. This serves as a shock or vibration reducing means.

The spring detent 44 carried by the cross piece 45 extending between the arms 32 engages the notch 46 in the member 31 and a corresponding notch or recess 47 in the section 35 as shown in dotted outline in Fig. 1.

I have shown the bolt 38 as a locking means for the handle but the bolt may be omitted particularly if it is not desired to lock the handle member in its collapsed position.

The screed is provided with rearwardly projecting arms 48 and 49 which carry the shaft 50 on which the rollers 51 are adjustably secured, the rollers being mounted between collars 52 adapted to be secured to the shafts in their adjusted positions. These rollers are normally out of engaging position when the screed and vibratory member are in operative supported relation to the forms. This permits the tilting of the machine onto the rollers to lift the vibratory and screed members from operative position for movement of the machine on the rollers. This is desirable where a second pass over the material being placed is desired as a result of there not being sufficient material supplied in the first instance to produce the desired strike-off level or where it is desired to get a more complete or perfect screeding finish. With this adjustable arrangement of the rollers, the machine is adapted for use on forms having quite a wide

variation in spacing which is a feature that has very substantial merit.

The vibratory member is provided with flexible loop-like retaining members 53, only one of them being illustrated in Fig. 1 as in the event the machine is used along side of a wall it is usually not objectionable if the concrete flows over the form. These retaining members are adjustably mounted on pairs of parallel rods 54 carried by the spaced brackets 55 on the front side of the vibratory member.

The guard members or retaining members 53 are in the form of loops of relatively stiff but somewhat flexible material such as reinforced belting, their inner ends being bolted to the clamp member 56, a coacting clamp 57 being provided to secure the members 53 in their adjusted positions on the rod.

The guard members are normally positioned over the forms as shown at the right hand side of Fig. 1. If desired, where one of the form members is close to a wall, the guard member shown by dotted lines at 58 may be secured to the supporting bracket 59. These retaining members serve to retain the vibrated concrete—that is, they prevent its overflowing the form member and also serve as brushes or wipers to prevent objectionable accumulation of concrete on the form members.

The screed member is provided with adjustable retaining members 60 carried by the clamps 61 secured to the screed member by means of the set screw conventionally shown at 62. Ordinarily these members 60 are adjusted so that they are positioned above the forms as shown at the right in Fig. 1. Again only one of these members is illustrated in the accompanying drawings but it will be understood that a second one is provided for use where one of the forms is not positioned close to a wall.

The machine or apparatus is easily manipulated by the workmen and is capable of being manipulated in confined spaces and close to the wall of a building or the like as indicated at 63 in Fig. 1.

The machine is of large capacity and highly efficient and has a wide range of adaptation.

I have not attempted to illustrate or describe the various possible adaptations or embodiments which I contemplate as it is believed that this disclosure will enable those skilled in the art to embody or adapt the invention as may be desired.

Having thus described my invention, what I claim as new and desire to secure by Letters Patent, is:

1. In a concrete placement machine, the combination of, a plank-shaped vibratory member disposed vertically edgewise and adapted to support forwardly thereof a substantial mass of concrete as it is advanced against the same, a plank-shaped screed member disposed vertically edgewise in substantially rearwardly spaced relation to said vibratory member, vibration absorbing connections between said vibratory and screed members whereby they are connected as a unit and coat to mutually support each other in upright position, an electric motor having an unbalanced rotor mounted on said vibratory member, a handle comprising inner and outer telescopic sections, one section being provided with diverging arms secured to the rear member, the other section being provided with a handle bar, locking means on said vibratory member, a latch mem-

ber mounted on the rear end of said other section for engagement with the locking means when the handle is in extended position, said latch member having a flexible vibration absorbing portion between the handle and the vibratory member, means for coupling said handle sections in collapsed position, and roller supporting arms projecting rearwardly from said screed member and provided with rollers at their rear ends whereby the machine may be tilted on the rollers to lift the vibratory and screed members from operative position for translation of the machine on the rollers, the rollers being normally out of engagement with forms on which the vibratory and screed members may be supported in operative position to work.

2. In a concrete placement machine, the combination of a plank-shaped vibratory member disposed edgewise and adapted to support forwardly thereof a substantial mass of concrete as it is advanced against the same, a plank-shaped screed member disposed edgewise in substantially rearwardly spaced relation to said vibratory member, vibration absorbing connections between said vibratory and screed members whereby they are connected as a unit and coact to mutually support each other in upright position, an electric motor having an unbalanced rotor mounted on said vibratory member, a handle comprising inner and outer telescopic sections, one section being provided with diverging arms secured to the rear member, the other section being provided with a handle bar, locking means on said vibratory member, a latch member mounted on the rear end of said other section for engagement with the locking means when the handle is in extended position, said latch member having a flexible vibration absorbing portion between the handle and the vibratory member, and roller supporting arms projecting rearwardly from said screed member and provided with rollers at their rear ends whereby the machine may be tilted on the rollers to lift the vibratory and screed members from operative position for translation of the machine on the rollers, the rollers being normally out of engagement with forms on which the vibratory and screed members may be supported in operative position to work.

3. In a concrete placement machine, the combination of a vibratory member adapted to support forwardly thereof a substantial mass of concrete as it is advanced against the same, a screed member disposed rearwardly of said vibratory member, vibration absorbing connections between said vibratory and screed members whereby they are connected for manipulation as a unit, means for vibrating said vibratory member, a handle comprising inner and outer telescopic sections, one section being secured to the screed member, vibration absorbing means detachably connecting the other section with the vibratory member when the handle is extended, and means for coupling said handle sections in extended position.

4. In a concrete placement machine, the combination of a vibratory member adapted to support forwardly thereof a substantial mass of concrete as it is advanced against the same, a screed member disposed rearwardly of said vibratory member, vibration absorbing connections between said vibratory and screed members whereby they are connected for manipulation as a unit, means for vibrating said vibratory member, a handle comprising inner and outer telescopic sections, one section being secured to the screed member, and vibration absorbing means detachably con-

necting the other section with the vibratory member when the handle is extended.

5. In a concrete placement machine, the combination of a plank-shaped vibratory member disposed vertically edgewise and adapted to support forwardly thereof a substantial mass of concrete as it is advanced against the same, a plank-shaped screed member disposed vertically edgewise in substantially rearwardly spaced relation to said vibratory member, vibration absorbing connections between said vibratory and screed members whereby they are connected as a unit and coact to mutually support each other in upright position, means for vibrating said vibratory member at high frequency, a handle secured to said screed member, a vibration absorbing connection between said handle and said vibratory member, and rollers supported at the rear of said screed member whereby the machine may be tilted on the rollers to lift the vibratory and screed members from operative position for translation of the machine on the rollers, the rollers being normally out of engagement with forms on which the vibratory and screed members may be supported in operative relation to work.

6. In a concrete placement machine, the combination of a plank-shaped vibratory member disposed vertically edgewise and adapted to support forwardly thereof a substantial mass of concrete as it is advanced against the same, a plank-shaped screed member disposed vertically edgewise in substantially rearwardly spaced relation to said vibratory member, vibration absorbing connections between said vibratory and screed members whereby they are connected as a unit and coact to mutually support each other in upright position, means for vibrating said vibratory member at high frequency, a handle secured to said screed member, and a vibration absorbing connection between said handle and said vibratory member.

7. In a concrete placement machine, the combination of a vibratory member adapted to support forwardly thereof a substantial mass of material as it is advanced against the same, a screed member disposed at the rear of said vibratory member, means for vibrating said vibratory member at high frequency, vibration absorbing connections between said members whereby they are connected for manipulation as a unit, a handle connected to the screed member, and vibration absorbing means connecting the handle to said vibratory member.

8. In a concrete placement machine, the combination of a vibratory member adapted to support forwardly thereof a substantial mass of concrete as it is advanced against the same, a screed member disposed rearwardly of said vibratory member, vibration absorbing connections between said vibratory and screed members whereby they are connected for manipulation as a unit, means for vibrating said vibratory member, a handle projecting forwardly of said vibratory member, and rollers mounted at the rear of said screed member on which the machine may be tilted to lift the vibratory and screed members from operative relation to work and for translation of the machine on the rollers when the handle is lifted, the rollers being normally elevated when the vibratory and screed members are in operative relation to work.

9. In a concrete placement machine, the combination of a vibratory member adapted to support forwardly thereof a substantial mass of concrete as it is advanced against the same, a screed

member disposed rearwardly of said vibratory member, vibration absorbing connections between said vibratory and screed members whereby they are connected for manipulation as a unit, means for vibrating vibratory member, a flexible retaining member projecting forwardly from the vibratory member, and means for adjusting said retaining member longitudinally of the vibratory member, said means including a rod disposed forward of and parallel to the vibratory member and including means for adjustably clamping said retaining member to said rod.

10. In a concrete placement machine, the combination of a vibratory member adapted to support forwardly thereof a substantial mass of concrete as it is advanced against the same, a screed member disposed rearwardly of said vibratory member, vibration absorbing connections between said vibratory and screed members whereby they are connected for manipulation as a unit, means for vibrating said vibratory member, a handle projecting forwardly of said vibratory member, and rollers mounted at the rear of said screed member on which the machine may be tilted to lift the vibratory and screed members from operative relation to work and for translation of the machine on the rollers when the handle is lifted, the rollers being normally elevated when the vibratory and screed members are in operative relation to work and mounted for independent adjustment longitudinally thereof.

11. In a concrete placement machine, the combination of a vibratory member adapted to support forwardly thereof a substantial mass of material as it is advanced against the same, a screed member disposed at the rear of said vibratory member, means for vibrating said vibratory member at high frequency, vibration absorbing connections between said members whereby they are connected for manipulation as a unit, a handle projecting forwardly of said vibratory member, and roller supporting arms projecting rearwardly from said screed member and provided with rollers on which the machine may be manipulated with the vibratory and screed members in elevated position when the handle is lifted, said rollers being mounted for adjustment axially of themselves and longitudinally of the screed.

12. In a concrete placement machine, the combination of a vibratory member adapted to support forwardly thereof a substantial mass of concrete as it is advanced against the same, a screed member disposed rearwardly of the vibratory member and connected thereto for manipulation as a unit, rollers mounted at the rear of the screed on which the machine may be tilted to lift the vibratory member and screed from operative relation to the work and for translation of the machine on the rollers, means supportingly associated with said vibratory screed members for tilting the machine on said rollers, the rollers being mounted for adjustment axially of themselves and longitudinally of the screed and being normally elevated when the vibratory and screed members are in operative relation to the work, and retaining members mounted on the vibratory member and extending forwardly therefrom, said retaining members being mounted for adjustment longitudinally of the vibratory member whereby the rollers and the retaining members may be

adjusted relative to the form for the material treated.

13. In a concrete placement machine, the combination of a vibratory member adapted to support forwardly thereof a substantial mass of concrete as it is advanced against the same, a screed member disposed rearwardly of the vibratory member and connected thereto for manipulation as a unit, and rollers mounted at the rear of the screed on which the machine may be tilted to lift the vibratory member and screed from operative relation to the work and for translation of the machine on the rollers, means supportingly associated with said vibratory screed members for tilting the machine on said rollers, the rollers being mounted for adjustment axially of themselves and longitudinally of the screed and being normally elevated when the vibratory members are in operative relation to the work.

14. In a concrete placement machine, the combination of a vibratory member adapted to support forwardly thereof a substantial mass of concrete as it is advanced against the same, a screed member disposed rearwardly of the vibratory member and connected thereto for manipulation as a unit, and retaining members mounted on the screed to project forwardly therefrom, said retaining members being mounted for adjustment longitudinally of the vibratory member whereby they may be adjusted relative to the forms for the material treated, said retaining members including inverted U-shaped attaching members engageable over the upper edge of the screed members.

15. In a concrete placement machine, the combination of a vibratory member adapted to support forwardly thereof a substantial mass of material as it is advanced against the same, a screed member disposed at the rear of the vibratory member in spaced trailing relation thereto, means for vibrating the vibratory member and mounted thereon, vibration absorbing connections between said members whereby they are connected for manipulation as a unit, a handle comprising inner and outer telescopic sections, one section being connected to the screed member, vibration absorbing means detachably connecting the other section of said handle to said vibratory member when the handle is in extended position, said means being engaged by a rotative movement of said other handle section, and means for coupling said sections in extended position engaged and disengaged by the rotative movement resulting in the engagement and disengagement of said connection for the handle to said vibratory member.

CORWILL JACKSON.
